C. A. COKER.

SANITARY VALVE FOR FLUID DISPENSING APPARATUS.
APPLICATION FILED SEPT. 3, 1918.

1,301,229.

Patented Apr. 22, 1919.

UNITED STATES PATENT OFFICE.

CLARENCE A. COKER, OF CORDOVA, ALABAMA.

SANITARY VALVE FOR FLUID-DISPENSING APPARATUS.

1,301,229.

Specification of Letters Patent. Patented Apr. 22, 1919.

Application filed September 3, 1918. Serial No. 252,325.

To all whom it may concern:

Be it known that I, CLARENCE A. COKER, a citizen of the United States of America, residing at Cordova, in the county of 5 Walker and State of Alabama, have invented certain new and useful Improvements in Sanitary Valves for Fluid-Dispensing Apparatus, of which the following is a specification.

10 This invention relates to improvements in sanitary valve attachments for the discharge spouts of fluid dispensing apparatus and particularly for syrup pumps for soda fountains and has for its object to produce a 15 spout which will be perfectly sanitary and which will have the distinguishing characteristic of providing a valve element carrying the discharge opening which is normally retracted into and serves to seal the open 20 end of the spout.

One object of my invention is to cause the valve element which carries the discharge opening to be sucked into the open end of the spout after the charge of fluid is discharged so that no part is left exposed over 25 which the fluid flows, thus preventing flies and dirt having access thereto.

A further object is to have this movable valve element serve as a plug or closure for 30 the open end of the spout so that it will hold the fluid standing in the delivery tube at a fixed level independent of the fluid level in the tank.

It is a further object of my invention to 35 utilize the pressure of the fluid in the tube to eject therefrom the discharge element and to utilize the suction pull of the fluid in the delivery tube to suck the discharge element back into its retracted position. To accomplish the latter effect, provision must be 40 made to close the delivery opening in said element so that the suction pull may become effective upon it and this may be done either by a valve movable automatically responsive 45 to the suction or movable by a spring.

My invention further comprises the novel 50 details of construction and arrangements of parts, which in their preferred embodiments only are illustrated in the accompanying drawings, in which:—

Figure 1 illustrates a syrup pump equipped with my improved type of nozzle with the discharge element in operating position.

Fig. 2 is an enlarged vertical sectional view 55 through the delivery end of the spout showing the parts in the position shown in Fig. 1.

Fig. 3 is a similar view of the parts with 60 the element in retracted position.

Fig. 4 is a bottom perspective view of the discharge element detached.

Fig. 5 is a vertical sectional view corresponding to Fig. 2 of a modification of my 65 invention.

Similar reference numerals refer to similar parts throughout the drawings.

I have illustrated my invention in connection with a typical soda fountain pump construction comprising a delivery cup 1 70 and delivery tube 2, a plunger 3 being disposed in the cup and operated by a plunger rod 4 which passes through a top plate 5 through which the delivery tube 2 also passes and is there connected to the spout 6 which 75 is mounted on said plate. All of the parts as thus described are of any standard construction except that the outer end 7 of the spout is adapted to receive a plug and fluid discharge element 8. This element 8 is in 80 the form of a tube closed at its outer end by a screw head 9 with a milled edge larger in diameter than the open end 7 of the spout, and tapered to form a valve 9a which will seat against a correspondingly tapered valve 85 seat at the outer end of the spout section 7. The member 8 is provided in its under face with a fluid discharge opening 10 and an elongated guide slot 11 and in its upper portion is cut away at 12 so as to leave at the 90 inner end of the member a complete circular open end portion 13. A lip or extension 14 of the member 8 is bent up opposite the open end 13 and a headed guide pin 15 is slidably inserted therethrough and carries at its inner end a sliding check valve 16, which in its closed position is drawn into and closes the end 13 of the tubular member 8 and in its open position moves opposite the notch 12 so as to permit the fluid to pass thereby to 95 the discharge opening 10. It will be noted that the member 8 makes a close sliding fit in the nozzle end 7 and that a set screw or stop pin 17 is inserted upwardly through the spout and works in the slot 11 and prevents 100 the rotation of the member 8 and limits its lengthwise movements.

In operation, the element 8 is inserted in

the end of the spout and the set screw 17 is caused to engage in the slot 11. On the depression of the plunger 3 the fluid to be dispensed is forced up through the tube 2 into the spout 6 until it reaches the element 8 where it acts to force the check valve 16 out of the tube end 13, thereby permitting the fluid to flow freely past the valve and into the member 8. The pressure of the fluid 5 then acts on the member 8 to eject it or force it outwardly from the spout until arrested by the pin 17 engaging the inner end of the slot 11. When in this position the discharge opening 10 will be exposed and fluid will 10 be discharged downwardly therefrom into the glass. As the plunger starts its up stroke the suction pull is exerted on the fluid in the tube 2 and spout 6 with the result that the check valve 16 is drawn inwardly 15 and closes the end 13 of the member 8. As soon as this occurs the suction pull is exerted on the member 8 as a whole and it is retracted into the spout until its taper valve 9^a seats with a tight joint in the open end of the 20 spout and seals the latter, causing the fluid to be arrested at a predetermined point in the delivery tube 2 with the resulting very great advantage of causing each operation of the pump to discharge a uniform volume of 25 fluid independently of the fluid level in the tank.

In Fig. 5 I show a slightly modified construction of the discharge element 8 which is here in the form of a tube or sleeve 18 which 30 is closed at its outer end by a tightly fitting screw cap 19 and is provided with a fluid discharge opening 10, a bottom longitudinal slot 20, corresponding to 11, in which the set screw or pin 17 in the delivery end 7 of the 35 spout engages. The outer end of the tubular member 18 is closed and receives therein a coiled spring 21 which acts to press a sliding sleeve valve 22 inwardly into position against a stop 23 in which position it serves to close 40 the discharge opening 10. This sleeve valve is closed at its outer end by a head 24 which the spring 21 engages. In the operation of this modified form the pressure of the fluid first acts against the valve 22 to move it outwardly and compress the spring 21, in doing 45 which the whole member 18 is carried outwardly so that by the time the valve 22 has cleared the opening 10 the member is in its outermost position. At the completion of 50 the plunger's pressure stroke, the pressure drops in the delivery tube, the spring 21 moves the valve 22 to close the opening 10 and the suction pull of the fluid draws the sleeve 18 back into retracted position into 55 the spout, closing the latter and concealing all but the outer end of the sleeve.

In both arrangements no part is left exposed over or through which the fluid flows and thus it will be impossible to have the 60 fluid contaminated by flies, dirt or germs

which naturally exist where the spout's discharge opening is exposed. The screw closures 9 and 19 for the discharge elements are removable to permit the latter to be thoroughly cleaned.

It will be understood that the particular design of the element 8 or 18 may be widely modified without departing from the broadly novel features of my invention which contemplate any retractable discharge element 75 which will protect the fluid discharge opening when not in service and which preferably will also serve to hold the fluid to be dispensed at a fixed level in the delivery tube.

Having thus described my invention, what I claim as new and desire to secure by Letters Patent, is:—

1. In a fluid dispensing apparatus, the combination with a delivery spout and plunger feed means to force fluid to be dispensed 85 therethrough, of a plug having a hollow body which fits with a close sliding fit into the spout and has a spout closing head at its outer end, there being an intermediate discharge opening in said plug body, means in 90 the plug to automatically close said discharge opening at the completion of the plunger's fluid expelling stroke to permit the suction stroke of the plunger to automatically retract the plug therefrom.

2. In a fluid dispensing apparatus, the combination with a delivery spout and a plunger force feed means to eject the fluid to be dispensed through said spout, of a plug 100 mounted in and adapted to normally close the spout's open end and having a fluid discharge port extending therethrough and opening through its side, a pressure opened valve normally closing said port, and means to limit the outward movement of said plug 105 to a position exposing said discharge port, said plug being reciprocable automatically responsive to the fluid pressure in the spout, substantially as described.

3. In combination with a syrup pump and its delivery spout, a plunger feed therefor, a plug closure reciprocable in the open end of said spout automatically responsive to the fluid pressure in the spout, means to limit and guide the reciprocable movements of said plug, there being a fluid discharge passage through said plug which is inclosed in the spout when the plug is in retracted position, and a check valve to close said passage on the suction stroke of the plunger.

4. The combination with a syrup pump and its delivery spout, said spout having an elongated discharge end, of a sleeve closure 125 slideable in said end and having a syrup discharge passage therethrough, valve means carried by the sleeve and movable automatically responsive to the syrup pressure, said valve means being adapted to close off communication between the open end of said passage and the spout when the syrup is not 130

under pressure, and guide means for the sleeve in said spout, substantially as described.

5. In combination with a fluid dispensing apparatus having a force feed for the fluid and a delivery spout therefor, of a plug reciprocable in the open end of the spout and having a fluid discharge port therein which is normally housed in the spout, a valve at 10 the outer end of the plug adapted to seal the open end of the spout when the plug is retracted, valve means automatically responsive to pressure conditions in the spout to control communication between the spout and 15 the open end of said discharge passage, and means to guide and limit the reciprocable movements of the plug responsive to the internal pressure conditions in the spout.
6. In a fluid dispensing apparatus, a spout, 20 a fluid pump adapted to force the fluid to be dispensed through said spout, an elongated element reciprocable in the spout automatically responsive to pressure conditions there-

in and having at its outer end a valve adapted to seal the open end of the spout in the 25 valve's closed position, there being a fluid discharge passage opening through the inner end and the side of said element, a suction responsive valve to close said passage, and means to guide and limit the reciprocatory 30 movements of said valve element.

7. In a fluid dispensing apparatus, a spout, an elongated sleeve having a sliding fit in the open end of the spout, a screw head which closes the open end of the sleeve and forms a 35 valve to seal the open end of the spout, an outlet port in the sleeve near said head, an automatic pressure responsive valve in the sleeve to close communication between said port and the spout, and means to guide and 40 limit the reciprocatory movements of said sleeve.

In testimony whereof I affix my signature.
CLARENCE A. COKER.
